(No Model.)

O. W. ALLEN.
STATION INDICATOR.

No. 596,284.

Patented Dec. 28, 1897.

UNITED STATES PATENT OFFICE.

ORRIE WALTER ALLEN, OF BUTTE, MONTANA.

STATION-INDICATOR.

SPECIFICATION forming part of Letters Patent No. 596,284, dated December 28, 1897.

Application filed December 2, 1896. Serial No. 614,199. (No model.)

To all whom it may concern:

Be it known that I, ORRIE WALTER ALLEN, residing at Butte, in the county of Silver Bow and State of Montana, have invented a new and useful Station-Indicator, of which the following is a specification.

This invention relates generally to station-indicators, and more particularly to a station or street indicator adapted for use in railway 10 and street cars to be operated by the conductor.

The object of the invention is to provide an exceedingly cheap and simple device which can be attached to the cars now in use and 15 can be easily operated by the conductor, and another object is to provide a station-indicator which can be easily reversed any time, so as to indicate correctly the stations as the car travels back and forth over a definite route. 20 With these various objects in view my invention consists in the peculiar construction of the various parts and in their novel combination or arrangement, all of which will be 25 fully described hereinafter, and pointed out in the claims.

In the drawings forming a part of this specification, Figure 1 is a view showing the practical application of my invention. Fig. 2 is a detail perspective view of the indicator 30 mechanism. Fig. 3 is a vertical sectional view. Fig. 4 is a front elevation. Fig. 5 is a detail perspective view of the valve operative reverse and pawl. Fig. 6 is a detail perspective view showing the belt-tightener. Fig. 7 is a detail perspective view of one of 35 the journals.

In carrying out my invention I employ a casing A, having an opening B in the front thereof, through which a ribbon D, bearing 40 the name of the station, is exposed. The ribbon D is attached to and wound upon the upper roller E and lower roller F, said rollers being journaled between uprights G, mounted within the casing A, the shafts of said rollers being fitted in the journal-bearings H, which are secured in the uprights, as most clearly shown in Fig. 2, said bearings being provided with lugs H', which securely hold them against rotation. The end of the roller E extends 45 beyond the uprights G at each side, and upon one end is arranged a toothed disk I, while at the opposite end is arranged a sprocket K.

A bifurcated lever L is attached to the end of the roll adjacent to the toothed disk I, said lever carrying the pawls M, which pawls are 55 adapted to engage the teeth of the disk I, and in order to hold one pawl in engagement while the other pawl is out of engagement I employ a stop device N, which is secured to the lever by means of a set-screw N', so that the said 60 stop will rest directly above the pawl to be held in engagement.

In the drawings I have shown the left-hand pawl in engagement, so that the operation of the lever will wind the ribbon upon the 65 roller E.

When it is intended to reverse the motion of the ribbon, the stop N is detached from the lever, reversed, and attached to the opposite side. The operation of the lever will then 70 cause the top roll E to unwind the ribbon, which ribbon is then wound upon the bottom roll F, and in order to transmit the motion from the top to the bottom roll I employ a sprocket chain or belt O, which passes around 75 the sprocket K at the end of the top roll and the sprocket K' upon the end of the bottom roll, said belt or chain being held taut by means of an idler-sprocket P, mounted upon the end of a plate P', which is slotted longitudinally, 80 as at P², and is adjustably secured to a plate P³ by means of a screw P⁴ and nut P⁵. The plates P' and P³ have their opposing faces serrated, as shown at P⁶, so that the plate P' can be adjusted in or out and readily secured 85 in the adjusted position. This action will permit the sprocket chain or belt to be tightened whenever desired. Guide-rolls R are arranged between the uprights G, near the front of the casing, in order to hold the ribbon 90 close to the opening in the casing. The lever L will of course be provided with suitable spring-actuated means for returning it to its normal position after it has once been operated. Operating belt or stop S is attached to 95 the lever and extends to the conductor's platform, from which he can readily operate the indicator.

It will thus be seen that I provide an exceedingly cheap and simple construction of 100 station-indicator, and the operation of the same is as follows: The conductor pulls upon the straps S, which operate the lever L, so that the pawl engages the toothed disk and moves

the same in the desired direction step by step, which operation winds up the ribbon upon one roll and unwinds it from the other roll, and in so doing the ribbon is caused to pass 5 across the opening in the casing, and on this ribbon are the names of the different stations. Moreover, it is clear that at each operation of the device the name of the proper station is brought into view. When the end of the route 10 has been reached, the stop N is removed from the lever L, reversed, and attached to the opposite side of the lever. The device is then ready for operating in a reverse direction. Should the drive chain or belt become slack 15 at any time, the idler-sprocket can be adjusted to take up the slack.

Having thus described my invention, what I claim as new, and desire to secure by Letters Patent, is—

20 1. In a station-indicator, the combination of supporting-frame, two rolls journaled in said frame, the shaft of one of them projecting beyond said frame, two guide-rolls also journaled in the frame, a ribbon on which appear 25 the names of the stations passing over the guide-rolls and having its ends secured to the winding-rolls, a toothed disk on the pro-

jecting ends of the winding-rolls, a bifurcated lever straddling said disk, a reversible pawl mounted in said lever, a removable and reversible device adapted to be placed and secured in reversible positions on the said lever, and a set-screw for securing it in place, all substantially as set forth. 30

2. In a station-indicator, a frame or combination with an upper and lower winding-roll mounted in said frame with their shafts projecting through the side thereof, sprocket-wheels mounted on these projected ends, a sprocket-chain around and engaging said 40 wheels, a plate secured to the side of the frame having teeth on its outer side, a second plate mounted on the first and having corresponding teeth to engage those of the first plate, a screw to adjust the position of these plates 45 with relation to each other, and a sprocket mounted on the adjustable plate and adapted to be adjusted in contact with the sprocket-wheels, all substantially as set forth. 35

ORRIE WALTER ALLEN.
